DESIGN FOR A CHAIR BACK

John B. O'Connor, Aurora, Ill., assignor to Lyon Metal Products, Incorporated, Aurora, Ill., a corporation of Illinois

Application May 3, 1938, Serial No. 76,945

Term of patent 14 years

To all whom it may concern:

Be it known that I, John B. O'Connor, a citizen of the United States, residing at Aurora, in the county of Kane and State of Illinois, have invented a new, original, and ornamental Design for a Chair Back, of which the following is a specification, reference being had to the accompanying drawing, forming part thereof.

The figure is a perspective view of a chair back, showing my new design.

The characteristic feature of my design resides in a chair back of the configuration shown having therein perforated areas arranged substantially as shown.

I claim:

The ornamental design for a chair back, substantially as shown and described.

JOHN B. O'CONNOR.
